FILER ATTORNEY

UNITED STATES PATENT OFFICE

WILMOT V. CASTLE, OF ROCHESTER, NEW YORK, ASSIGNOR TO WILMOT CASTLE CO., OF ROCHESTER, NEW YORK, A CORPORATION OF NEW YORK

STERILIZING APPARATUS

Application filed September 4, 1931. Serial No. 561,235.

This invention relates to sterilizing apparatus and has for its principal object a structure wherein a wash bowl and one or more sterilizers are brought together as a unit and intimately associated with a storage or supply cabinet to obviate the necessity of washing and drying instruments at one place and transporting same to a distant point for sterilizing or storing purposes.

10 In the use of the present apparatus the supply of fresh running water, hot or cold, or both, are at hand for the use of an attendant at the bowl for supply to the bowl or to one or more sterilizers, obviating the necessity of carrying water to the bowl from a remote point, thereby making for convenience and saving time, labor and annoyance.

With the above and other objects in view, the present invention consists in the combination and arrangement of parts hereinafter more fully described and illustrated herein, and particularly pointed out in the appended claims, it being understood that changes may be made in the form, proportion, size and minor details so long as departure is not made from the scope of the appended claims.

In the drawings:

Fig. 1 is a perspective view of one form of the invention;

30 Fig. 2 is a fragmentary sectional view on the line 2—2 of Fig. 1;

Fig. 3 is a vertical sectional view of the invention;

Fig. 4 is a horizontal sectional view;

35 Fig. 5 is an enlarged fragmentary longitudinal sectional view through the top and upper portion of the body of the cabinet.

Referring now more particularly to the accompanying drawings, the reference character 1 indicates a cabinet or other supporting means of any suitable design mounted upon a suitable base 2, having a recess 3 therein, of a length and width to accommodate two foot pedals 4 and 5 within the confines of the base, so as not to result in projections liable to trip a person and which are adapted to be foot manipulated, separately, for the supply of hot and cold water, as will be later explained.

50 The interior of the cabinet may be pro-

vided with shelves or compartments or both (not shown) and may have a transparent or other door 6. In any event, the cabinet proper is preferably formed of molded material of any suitable character and is open at its 55 upper end.

A hollow top member A is provided for the cabinet and it is preferably formed of molded material but may be otherwise produced, if desired. As illustrated, the top 60 A includes an upper or top wall 7 and a lower wall 8, the two walls being connected by a continuous highly ornamental outer side wall 9 which has a raised and rounded rib like formation 10 extending around the top to 65 prevent water or fluids running off the top, also to prevent instruments sliding off the top. The lower wall of the top A is preferably provided on its under face with a continuous groove 11 adapted to snugly receive 70 the top edge of the cabinet 1, as clearly illustrated in the drawings, and by virtue of which, the top A is effectively secured on the cabinet against accidental lateral displacement. If desired, a suitable cement may be 75 employed to fasten the upper edge of the cabinet in said groove 11.

A bowl C is arranged intermediate the ends of the top A. This bowl preferably has substantially front and rear walls 12 and 80 13, respectively, and curved end walls 14, merging into the curved bottom 15 of the bowl, there being a suitable waste outlet 16 from the bowl.

From the foregoing it will be seen that the 85 upper and lower walls 7 and 8 are connected by the outer side wall 9 and by the inner walls forming the bowl C, affording strength for the top A.

At opposite ends of the bowl or between 90 the ends of the bowl and the ends of the top, the top is provided with relatively large depressions 17 and 18, both preferably formed alike, and each extending as to length preferably transversely of the top. These depressions are relatively shallow but deep enough to receive sterilizers in such a manner as to prevent lateral movement of the sterilizers out of the depressions, as may be seen by reference to the sterilizer 19 in Fig. 1. While 100

only one sterilizer has been shown, it is obvious that a sterilizer is adapted to occupy the depression 17, if desired.

Each depression 17 and 18 has a relatively short, narrow, laterally directed extension 20 and 21, respectively, for the purpose of receiving drippings from a faucet 22 of a sterilizer so that such drippings may pass into the respective main depression and over the illustrated sloping walls of the latter to the respective drain passages 23 and 24 to the bowl, there being a groove forming drain passage 25 leading from the upper surface of the top to the bowl, whereby the top surface 15 face is maintained practically free of fluids.

Water, under pressure from any suitable source (not shown), may be let into the valve casings 26 and 27 located preferably within the cabinet. Both of these valve casings are alike and a detailed description of one is all that is necessary for an understanding of both. The valve casings communicate with each other through the pipe 28. In each valve casing is a valve stem 29 having a valve 25 30 normally held seated or closed by a spring 31. The aforesaid pedals 4 and 5 are each supported by a double armed lever 32 pivoted at 33 within the cabinet and having a bifurcated inner end 34 coacting with a pin 35 on the respective valve stem so that upon depression of a pedal the respective valve is lifted to permit water, hot or cold, to pass from the respective valve casing to the aforesaid pipe 28 through pipe 36 to the swiveled 35 36 goose-neck faucet 37 from which the water may be discharged into the bowl C or into a sterilizer at either end of the top of the cabinet, as may be seen upon reference to Figs. 1 and 3 of the accompanying drawings.

40 Thus, assuming that hot water flows through pipe 38 to its valve casing 26 and that cold water flows through pipe 39 to its valve casing 27, the depression of the proper foot pedal will effect a flow of hot or cold water or upon depression of both pedals at same time a mixture of both hot and cold water into pipe 28 from which it passes by way of pipe 36 to and through the faucet 37, as should be well understood.

50 In the event of water running down the sides of the sterilizers it will be seen that such water will pass into the respective depressions 17 and 18 and find its way into the bowl C.

55 It will be apparent that the top of the cabinet is free of joints, liable to cause leakage and create accumulations of foreign matter, and that the invention is compact in structure and highly useful in hospitals or in the offices of physicians, dentists or others, due particularly to the advantages afforded incident to the fresh running water, hot or cold or both, at hand, together with the sterilizers and wash bowl, the supply of water being easily and readily governed by an

attendant's foot with the operating pedals confined within a recess to prevent possibility of an attendant or other person tripping over the same. It will also be readily apparent that the top member may be supported on a supporting means other than a storage and supply cabinet and that in any event the corners and other parts of the bowl, depressions and other formations may be easily and readily cleaned and maintained in a sanitary condition.

70 The particular valve mechanism shown is for illustration purposes only. Any suitable type of valve mechanism may be employed in the use of the present invention.

80 What I claim as my invention and desire to secure by Letters Patent is:

1. An apparatus comprising a supporting means, a member mounted on the supporting means and having a depression in each end thereof adapted for the support of a sterilizer, a bowl on said member between said depressions with drain passages leading from said depressions to said bowl, the upper surface of said member along one side edge of the bowl between the depressions having a groove forming a drain to said bowl.

2. In an apparatus of the class described, a member having a depression in each end thereof adapted for the support of a sterilizer, a bowl on the rear portion of said member between said depressions with drain passages leading from said depressions to said bowl, the upper surface of said member which is along the front edge of the bowl and which is between the depressions having a rearwardly extending groove forming a drain to said bowl, said depressions each having a lateral extension communicating therewith adapted to receive drippings from a faucet of a sterilizer when in place on the member and to direct said drippings into the respective depression under the sterilizer when in place thereupon and from which depression the drippings pass into the bowl by way of the respective passage.

3. An apparatus of the class described comprising a supporting means, a member mounted on the supporting means and having a depression in each end thereof adapted for the support of a sterilizer, a bowl on said member between said depressions with drain passages leading from said depressions to said bowl, the upper surface of said member along one side edge of the bowl between the depressions having a groove forming a drain to said bowl, said depressions each having a lateral extension communicating therewith adapted to receive drippings from a faucet of a sterilizer when in place on said member and adapted to direct the flow of drippings received therein into the respective depression and from which depression the drippings flow into the bowl by way of the respective passage, and a swiveled faucet on

said member operable for the delivery of hot or cold water to the bowl or to a sterilizer when supported in either of said depressions, and foot operated means for governing the supply of the hot or cold water.

4. A bowl construction comprising a supporting means, a top member mounted on the supporting means and including upper and lower walls connected by a continuous side wall rising at its upper edge slightly above the upper surface of the top member, a bowl carried by the top member and connecting the upper and lower walls thereof, the top member having sloping depressions in its upper wall communicating with said bowl.

5. An apparatus of the class described comprising a supporting means and a top member mounted on the supporting means and including upper and lower walls connected by a continuous side wall rising at its upper edge slightly above the upper surface of the top member, a bowl carried by the top member and connecting the upper and lower walls, the top member having sloping depressions in its upper wall and provided with communicating passageways leading from said depressions to said bowl, said depressions each having a lateral extension communicating therewith adapted to receive drippings, from a faucet of a sterilizer when supported over said depression, each of which depressions is constructed so as to conduct drippings thus received in the extension thereof to the bowl by way of the respective communicating passageway between such depression and the bowl.

6. An apparatus comprising a supporting means, a top member mounted on the supporting means and including upper and lower walls connected by a continuous side wall rising at its upper edge slightly above the upper surface of the top member, a bowl carried by the top member and connecting the upper and lower walls, the top member having sloping depressions in its upper wall communicating with said bowl, the upper face of the upper wall having a groove therein forming a drain to the bowl, a swiveled faucet mounted on said top member and arranged so that at will it can deliver water into the bowl or into a space above either of the depressions, a water supply pipe leading to said faucet, and means governing the flow of water to the nozzle through said pipe.

7. A sterilizing apparatus comprising a hollow support, a hollow top member mounted on said support and having a depression therein at each end thereof, a bowl located at the rear portion of said top member but between said depressions and having communication therewith, said hollow top member having a front upper wall portion with a drain groove leading rearwardly to the bowl, and means for delivering water to the bowl or to points over either of said depressions.

8. A sterilizing apparatus comprising a cabinet open at its upper end, a top member having a continuous groove in its under surface to receive the upper open end of the cabinet whereby to close the upper end of the cabinet and to support the top member, a bowl carried by the top member, the top member having a sloping end depression therein which has a lateral drain passage communication with the bowl and a front top surface portion having a drain leading rearwardly to the bowl.

9. An apparatus of the class described comprising a hollow member of greater cross sectional diameter at its base than at any other portion thereof and provided with a recess at its base portion, a top member supported on said hollow member and having end depressions therein at the top thereof, a bowl carried by and constituting a part of the top member, said top member providing drain passages leading from said depressions to the bowl, said top member having a front portion of a top wall, which front portion is located between said depressions and drains into said bowl, a faucet mounted on the top member in a manner to supply water at will to the bowl or to a point over either one of the end depressions, means whereby to supply water to the faucet, and means having foot controlled levers located within the aforesaid recess for actuation in a manner to govern the supply of water to said faucet.

10. A sterilizing apparatus comprising a member having a depression therein at each end thereof, and a bowl carried by said member between said depressions and having drainage communication leading from each depression into the bowl, and an upper surface portion located between said depressions and having a drainage leading to the bowl.
